UNITED STATES PATENT OFFICE.

OTTO A. BELGER, OF NEWTONVILLE, MASSACHUSETTS, ASSIGNEE, BY MESNE ASSIGNMENTS, TO WHITIN MACHINE WORKS, OF WHITINSVILLE, MASSACHUSETTS.

COMBING MACHINE.

Application filed June 7, 1922. Serial No. 566,498.

To all whom it may concern:

Be it known that I, OTTO A. BELGER, a citizen of the United States, and resident of Newtonville, county of Middlesex, State of Massachusetts, have invented an Improvement in Combing Machines, of which the following description, in connection with the accompanying drawing, is a specification, like characters on the drawing representing like parts.

This invention relates to combing machines, and particularly to combing machines of that type which have a fan or suction apparatus for the purpose of removing the waste from the circular brush of the machine and keeping the machine free from dust during the working.

As illustrating combing machines of this type I would refer to the following United States patents to Roth, No. 905,233, Dec. 1, 1908 and Belger No. 1,106,073, August 4, 1914. These combing machines are usually driven by means of fast and loose pulleys, and the main shaft, which is driven by the fast pulley is operatively connected to a fan shaft from which the fan of the aspirator or other suction device is operated.

In operating combing machines of this type it is desirable that the fan or suction apparatus should continue to run for a period of time after the machine has come to rest in order that the suction action may continue sufficiently long to remove all the waste from the cylinder and brush, for if the suction action stops as soon as the machine stops there will be a certain amount of waste remaining on the cylinder and brush which will be detrimental to the combing operation when the machine is again started.

It is also highly desirable that the suction apparatus should begin to function and that suction should be developed as soon as the machine starts in operation.

It is one of the objects of my invention to provide a novel improved means for operating the fan of the combing machine so that these desirable results will be attained, that is, the fan will continue to develop suction for a predetermined time after the machine is stopped thereby completely clearing the cylinder and brush of waste, and the fan will start up at once when the machine starts so that there will be the proper suction action developed as soon as the machine is in operation.

I secure these results by providing a novel construction whereby when the machine is stopped the fan is allowed to run freely of its own momentum until it comes to rest and this operation of the fan will continue the suction action for a sufficient period of time after the machine has come to rest to clear the cylinders.

The fan driving mechanism is also constructed so that when the machine is started up by shipping the belt onto the fast pulley, the fan will be immediately set in operation to produce the necessary suction effect.

In order to give an understanding of the invention I have illustrated in the drawings a selected embodiment thereof which will now be described after which the novel features will be pointed out in the appended claims.

Fig. 1 is a side view of a portion of the frame of a combing machine showing the fan-operating mechanism.

Fig. 2 is a side view thereof.

Fig. 3 is a view of the fan-driving mechanism looking from the opposite side from that shown in Fig. 1 and showing the position of the parts when the driving belt is on the loose pulley.

Fig. 4 shows the position of the parts when the driving belt is on the fast pulley.

Fig. 5 is an enlarged section through the link 20.

Inasmuch as my invention relates to the mechanism for driving the fan of the aspirator or other suction device of a combing machine I have not thought it necessary to illustrate herein a complete combing machine but have only shown a sufficient portion thereof to enable my invention to be understood.

1 indicates a portion of a frame of a combing machine, which is provided with the driving shaft 2 on which is mounted the loose pulley 3 and the fast pulley 4, the pulley 4 being fast to the shaft 2. 5 indicates the driving belt by which the machine is driven and 6 is the belt shipper by which the belt is shipped from the fast to the loose pulley and vice versa. This belt shipper is shown as carried by a belt shipper arm 105 7 pivoted to the frame at 8 and having a shipper rod 9 connected to its lower end, as shown at 10.

11 indicates the fan shaft from which the fan of the aspirator or other suction

device (not shown) is operated. This fan shaft is driven from the driving shaft 2 by some suitable driving connection, which in the present embodiment of the invention is shown as a fan belt 13 passing around a fan-driving pulley 14 that is rigid with the pulley 4 and around a pulley 12 fast on the fan shaft.

The parts thus far described are or may 10 by all as usual in combing machines of the above type.

As stated above one object of my invention is to provide a novel construction by which the fan shaft will be started up as soon as 15 the belt is shifted onto the fast pulley 4 so that the proper suction will be developed as soon as the machine is started, and by which the fan will be allowed to operate for a period of time after the machine has 20 come to rest so that the suction action will be continued sufficiently long to clear the waste from the circular comb and brush.

I have provided for this herein by employing a belt 13 for driving the fan which 25 is normally loose enough to allow the fan shaft to rotate freely but which is automatically tightened when the driving belt 5 is shifted to the fast pulley and is loosened when the driving belt is shifted to the loose 30 pulley. With this arrangement the fan will be started up as soon as the belt 5 is shifted to the fast pulley, but when said belt is shifted to the loose pulley and the machine comes to rest the fan belt 13 is loosened 35 to such an extent that the fan can continue to rotate by its own momentum for a sufficiently long period of time to clear the waste from the circular brush.

In the construction herein shown the fan 40 shaft has loosely mounted on it an elbow lever 15, one arm 16 of which carries an idler pulley 17 which is adapted to bear against the belt 13 and tighten the latter. The other arm of the elbow lever is provided 45 with a weight 18, which when released, operates by gravity to bring the belt-tightening pulley 17 into operative position shown in dotted lines Fig. 2. When the elbow lever is swung into the full line position 50 Fig. 2 the belt-tightening pulley 17 is removed from engagement with the belt 13 so that the latter is loose.

Means are provided for operating the elbow lever 15 in unison with the operations 55 of the belt shipper 7. The end 19 of the elbow lever 15 extends loosely through one end of a link 20, the other end of said link being pivoted at 21 to the upper end of a lever 22 which is pivoted at its lower end to a stand 23 as shown at 24. This lever is provided intermediate of its ends with a slot 25 through which extends a pin 30 projecting from the shipper rod 9.

When the driving belt 5 is on the loose 60 pulley, as shown in Fig. 1, the belt shipper

7 and shipper rod 9 will be in the positions shown in Fig. 3. When the shipper rod is in this position the lever 22 stands substantially vertically and the elbow lever 15 is held in its elevated position with the belt-tightening pulley 17 in its inoperative position.

When the belt shipper 7 is swung into the position to ship the belt 5 to the fast pulley 4, the shipper rod 9 is moved into the position shown in Fig. 4, thus swinging the lever 22 to the right and allowing the elbow lever 15 to swing into the dotted line position Fig. 2 under the influence of the weight 75 18. When in this position the belt-tightening pulley 17 engages the belt 13 and tightens the latter so that the fan shaft will be driven. This tightening of the fan belt occurs simultaneously with the shipping of the driving belt onto the fast pulley so that 80 the fan will start up just as soon as the machine is started.

When the machine is stopped by shipping the belt onto the loose pulley 3, this operation 90 swings the lever 22 into the position shown in Fig. 3 thereby operating through the link 20 to lift the elbow lever 15 into the full line position Fig. 2, which removes the belt-tightening pulley 17 from contact with the belt and loosens the fan belt sufficiently 95 so that the fan can run freely by its own momentum. It will be understood that when the fan is in operation it is rotating very rapidly and as soon as the fan belt is loosened it will continue to rotate for a period of time under its own momentum. The machine as a whole, however, will come to rest quickly when the belt is shifted onto the loose pulley so that the fan continues 100 to operate for a sufficient period of time after the machine comes to rest to insure that the circular brushes will be freed from waste.

The link 20 is so constructed that it will 110 act as a thrust member only, it being operative to swing the elbow lever from the dotted to the full line position Fig. 2 against the action of the weight 18 but having no positive action in swinging the elbow lever from the full to the dotted line position. This link is shown as comprising the parts 115 33 and 34, the part 33 having a socket 35 to slidably receive the end of the part 34. The part 34 is screw-threaded and is provided with stop nuts 36 thereon which by their engagement with the end of the part 33 determines the extent to which the link can contract. In setting up the machine this link will be adjusted as to its length 120 so that when the parts are in the position shown in Fig. 4 and the belt-tightening pulley 17 is in the dotted line position Fig. 2 there will be a slight clearance between the nuts 36 and the end of the part 33. The link 20, therefore, does not at this time 125 130

furnish any support for the elbow lever and for loosening the fan-driving belt when the full benefit of the weight 18 is secured in holding the pulley 17 against the belt. When the belt is shifted onto the loose

5 pulley, however, the first movement of the lever 22 will raise the part 34 to bring the nuts 36 against the part 33 and thereafter the link 20 is operative as a strut to raise the elbow lever 15 into the full line position

10 Fig. 2. The purpose of this loose connection in the link 20 is so that when the belt-tightening pulley is in its operative position it has the full benefit of the weight 18 in holding the belt 13 taut.

15 It will thus be seen that my invention comprehends a driving mechanism for the fan which is constructed so that it will allow the fan to rotate freely under its own momentum after the machine is stopped, 20 but will start the fan up instantly when the machine is started, and while I have illustrated herein one construction operating in this manner yet I wish it understood that the invention is not limited to the 25 form shown but may include other constructions which will accomplish this purpose.

I claim,

1. The combination with a combing machine having a main driving shaft, fast 30 and loose pulleys thereon, a belt shipper by which the driving belt is shipped from one pulley to the other, and a fan shaft from which the fan is operated, of means for driving the fan from the driving shaft, 35 said means including a fan-driving belt which is normally sufficiently loose so that it is ineffective for power transmission purposes and means operated by the belt shipper to tighten said fan-driving belt when the 40 driving belt is shipped onto the fast pulley

and for loosening the fan-driving belt when the driving belt is shipped onto the loose pulley.

2. A combing machine having in combination a main driving shaft, fast and loose 45 pulleys thereon, a belt shipper by which the driving belt is shipped from one pulley to the other to start and stop the machine, a fan shaft from which the fan is driven, a fan-driving belt pulley fast on the driving 50 shaft, a belt pulley on the fan shaft, a fan belt encircling the belt pulley and the fan-driving pulley and normally being sufficiently loose to permit the fan shaft to rotate freely, and means operated by the belt 55 shipper for tightening the fan belt when the driving belt is shipped onto the fast pulley and for loosening the fan belt when the driving belt is shipped onto the loose pulley.

3. A combing machine having in combination a main driving shaft, fast and loose 60 pulleys thereon, a belt shipper by which the driving belt is shipped from one pulley to the other, a fan shaft from which the fan is driven, a fan belt for driving the fan 65 shaft from the main shaft, said belt being normally sufficiently loose to permit the fan to rotate freely by its own momentum, a weighted elbow lever pivotally mounted on the fan shaft, a belt-tightening pulley carried by said lever, and a connection between 70 said lever and the belt shipper by which the belt-tightening pulley is rendered inoperative when the driving belt is on the loose pulley and operative when the driving 75 belt is on the fast pulley.

In testimony whereof, I have signed my name to this specification.

OTTO A. BELGER.
